UNITED STATES PATENT OFFICE.

CARL GEORGE DABIS, OF CHICAGO, ILLINOIS.

PILE AND PANEL SYSTEM FOR CONCRETE CONSTRUCTION.

1,362,852.

Specification of Letters Patent. Patented Dec. 21, 1920.

Application filed September 2, 1919. Serial No. 321,118.

To all whom it may concern:

Be it known that I, CARL GEORGE DABIS, a citizen of Transvaal, South Africa, and a resident of the city of Chicago, in the county 5 of Cook and State of Illinois, have invented a new and useful Improvement in Pile and Panel Systems for Concrete Construction, of which the following is a full, clear, and exact description.

10 My invention relates to improvements in concrete constructions preferably for use under water, and it consists in the combinations, constructions and arrangements herein described and claimed.

15 An object of my invention is to provide a device which may take the place of caissons or coffer dams.

20 A further object of my invention is to provide a sub-aqueous concrete construction 20 which may be readily installed, and which when installed partakes of the nature of a monolithic structure.

25 A further object of my invention is to provide a sub-aqueous construction which 25 may be installed at relatively low cost.

30 Other objects and advantages will appear in the following specification, and the novel features of the invention will be particularly pointed out in the appended claims.

35 My invention is illustrated in the accompanying drawings, forming part of this application, in which—

Figure 1 is a section through a portion of the construction,

35 Fig. 2 is a sectional view of a portion of a modified form,

Fig. 3 is a side view of one of the piles,

Fig. 4 is a section along the line 4—4 of

Fig. 3,

40 Fig. 5 is a section along the line 5—5 of Fig. 3, and

Fig. 6 is a sectional view showing another modified form.

Fig. 7 is a sectional view through the 45 double panel wall with a single row of piles.

Referring now particularly to Figs. 1, 3, and 4, I have shown therein a pile or post having a body portion 1 in the shape of a cross. Each of the arms of the cross is pro-

50 vided with a shoulder 2. These shoulders form extensions of the cross, and the pile tapers downwardly from the shoulders to the bottom, the bottom of the pile being square, as shown in Fig. 5. The pile is pro- 55 vided with a metal pile shoe 3 to facilitate the driving of the pile. At various inter-

vals dowel pins 4 are provided, these pins extending into the spaces between the adjacent arms of the cross. If desired, reinforcing material, such as rods or bars (not 60 shown), may be used in strengthening the pile. In each arm of the cross is a vertically disposed guide groove 5 extending to one of the outer faces of the arm. In the drawings, it will be seen that the grooves are so 65 located that there is always one groove for each side or face of the pile. The grooves are enlarged at their interior ends.

Arranged to coöperate with the piles are panels or slabs 6 which are made of concrete, 70

preferably reinforced. Each of these panels is provided with a recess 7 on its outer face at each end of the panel. The panels are designed to rest on the shoulders 2 in the manner shown in the drawings, with their 75 ends spaced apart. The panels are lowered into position after the piles are set, guide piles 8 being provided for facilitating the guiding of the slabs into their proper position.

Each slab is provided with a guide bolt or pin 9 which is carried in a threaded socket 10, embedded in the inner face of the slab. The heads of the guide bolts pass 80

within the vertical grooves 5, so that the ends of the panels are spaced apart at the proper distance. Each panel is provided 85

with a groove 11 arranged to receive the ends of a metal retaining member 12. The latter is preferably in the form of a corrugated sheet metal strip whose ends are fas-

90 tened to cylindrical rods or wires which may be slipped downwardly in the grooves 11 so as to retain the member 12 in position.

When the panels are in position, the space 95 between the ends of the panels is filled with grout 13 by means of a tube. When this hardens, it binds the ends of the panels together, and also binds them to the piles, thus making a monolithic structure.

100 In Fig. 1, I have shown the panels as attached only on one side of the pile. This is useful for light wharves without heavy traffic, as, for instance, in passenger landings, also for waterways with little or no

105 current, to protect the bank against erosion caused by the wash of passing vessels. In such cases, the panels may be placed on the inside of the piles, jetted in place, and are kept there by the pressure of the back fill when the piles are not endangered from 110 damage through drifting logs, etc.

110 In Fig. 2, I have shown a double wall con-

struction. In this figure also, the piles are turned 45° from the position shown in Fig. 1. In Fig. 2 the panels 6 are secured at their ends to a pile which has its guide 5 grooves 5 in the ends of the arms. In this form of construction, two piles are placed near each other to support the opposed ends of the section, but are spaced apart, so that the grout is placed in the space between the 10 ends, to form what I might term a two pile joint as distinguished from the single pile joint on one side only of the pile of the construction shown in Fig. 1. In the construction shown in Fig. 2 the space between the 15 slabs or panels is filled with concrete by means of a tube under water, being held by reinforcing hooks or stays 19.

In Fig. 6, I have shown a modified form of the device. In this figure a pile 21 has a 20 vertical face on one side thereof to receive a panel 22 which rests on a shoulder 23. The opposite side of the pile is provided with an inclined extension 24 which terminates at its bottom in an integral prolongation 25 of the pile, a bracing member 26 being provided, as shown. In this form of the construction, the pile is driven in place and a panel 27 is laid with its face against the inclined extension 24. The bottom of 30 the panel is provided with an outwardly extending integral flange or foot 28. It will be understood that the panels are grouted together in this form of construction precisely as in the other forms. The space between the opposed panels 22 and 24 is filled with concrete 29 in the manner described, thus making a very solid structure.

A number of different advantages arise 40 from the use of my improved concrete construction. In the first place, the peculiar cross shape gives the pile a greater stiffness and friction load capacity than any other shape. The use of the pile and panel system saves the building of a separate coffer-dam and the work of removing the same. It saves also the building of separate form walls and their removal and consequently 45 it is the means of saving considerable material, labor, and time.

50 In the use of my improved construction for coffer-dams, there is another advantage. In the ordinary coffer-dam the leakage necessitates continual pumping out. In the monolithic structure described herein, after the 55 water has been once pumped out, there is no necessity of further pumping, because there is no leakage through the solid concrete wall.

60 For extra deep water work, the double panel style, shown in Fig. 7 is used as a coffer-dam and outer shell in the same manner as the single style, in lighter constructions.

65 Obviously, other uses than those described might be made of my improved sub-aqueous

construction. I consider as my own, however, all such modifications as fairly fall within the spirit and the scope of the invention.

While my invention is primarily intended 70 for sub-aqueous use it is obvious that the constructions presented may be used on dry land.

I claim:

1. A concrete construction comprising a 75 series of concrete piles spaced apart, each of said piles having a straight body portion and a tapered portion integral with said body portion and having shoulders at the top of the tapered portion and a series of concrete 80 panels or slabs arranged to rest on the shoulders of the piles to form a wall.

2. A concrete construction comprising a series of piles spaced apart, each of said piles having a shoulder and a series of concrete 85 panels or slabs adapted to rest on the shoulders of the piles, and means for joining the ends of the panels together to form a monolithic structure.

3. A concrete construction comprising a 90 plurality of concrete piles having shoulders, a plurality of concrete panels arranged to rest on the shoulders, each of said panels having a recess at its ends, and a concrete binding material disposed in the registering 95 recesses of the ends of the adjacent panels.

4. In a concrete construction, a concrete pile having a straight body portion and a tapered portion integral with said body portion and having shoulders at the top of the 100 tapered portion, said straight body portion and said tapered portion having a cross section the shape of a cross.

5. In a concrete construction, a concrete pile having a cross section the shape of a 105 cross, and being provided with shoulders and dowel pins arranged to project into the spaces between the arms of the cross.

6. In a concrete construction, a concrete pile having a cross section the shape of a 110 cross, and being provided with shoulders and dowel pins arranged to project into the spaces between the arms of the cross, said piles having longitudinally extending guide grooves projecting from the faces thereof. 115

7. In a concrete construction, concrete piles having a cross section the shape of a cross, and being provided with shoulders and dowel pins arranged to project into the spaces between the arms of the cross, said 120 piles having longitudinally extending guide grooves projecting from the faces thereof, and concrete panels having guide members arranged to enter said guide grooves for guiding the panels to seat on said shoulders.

8. In a concrete construction, a plurality of concrete piles spaced apart, each of said piles having a straight body portion and an integral tapered portion provided with 130

shoulders at the top, a plurality of concrete panels arranged to rest on said shoulders, the ends of the panels being spaced apart and being provided with recesses, and concrete binding material disposed in said recesses.

9. In a concrete construction, a plurality

of concrete piles spaced apart and having shoulders on their opposite sides, panels arranged to rest on said shoulders, means for joining the ends of adjacent panels together, and a filling material disposed between the opposed panel sections.

CARL GEORGE DABIS.
